UNITED STATES PATENT OFFICE.

BLANCHE ELSIE BEADLE, OF SPRINGFIELD, MASSACHUSETTS, ASSIGNOR OF ONE-HALF TO RUSSELL A. BEADLE, OF SPRINGFIELD, MASSACHUSETTS.

HAIR-CLASPING DEVICE.

1,408,247.

Specification of Letters Patent. Patented Feb. 28, 1922.

Application filed November 17, 1920. Serial No. 424,718.

To all whom it may concern:

Be it known that I, BLANCHE E. BEADLE, citizen of the United States, residing at Springfield, in the county of Hampden and 5 State of Massachusetts, have invented new and useful Improvements in Hair-Clasping Devices, of which the following is a specification.

This invention relates to an improved hair-clasping device which may be used for a 10 curler, barrette, or analogous purposes, and constitutes an improvement upon the construction disclosed in my copending application Serial No. 400,360, filed July 31, 1920.

15 It is desirable in devices of this character to provide means for positively retaining the parts in latched position and prevent them from becoming disengaged and at the same time provide a simple and easily manipulated form of latching mechanism which 20 will not become entangled in the hair and which, while securely holding the parts against accidental disengagement, can be readily released when desired.

25 Another object of the invention is to provide a device of this character having means for latching the free ends of the arms together in such a manner as to prevent longitudinal movement of one arm relative to 30 the other and thus insuring that they be held in latched position.

Other objects and advantages of the improved construction will be apparent from the following detailed description of the 35 structure and its mode of operation.

Referring to the drawings:

Fig. 1 is a side elevational view of the device, showing the parts in their normally expanded position;

40 Fig. 2 is a top plan view of the structure shown in Fig. 1;

Fig. 3 is a detail side view, showing the parts in latched position;

45 Fig. 4 is a perspective view of a modified form of latching mechanism, showing the position of the parts when the latch is released;

50 Fig. 5 is a perspective view of the structure shown in Fig. 4, showing the parts in latched position;

Fig. 6 is a perspective view of a further modified form of latching mechanism;

Fig. 7 is a detail side view of the latch mechanism shown in Fig. 6;

Fig. 8 is a perspective view of another modified form of latch mechanism; and

Fig. 9 is a detail side view of the latch mechanism shown in Fig. 8.

In the embodiment of the invention illustrated herewith, 1 designates the main body portion of the device, which is preferably formed of a strip of resilient material bent upon itself to form two resilient arms 2 and 3 of substantially equal length. These arms are connected by a loop-shaped portion 4, 65 which is of such form as to materially enhance the resiliency of the arms and to permit the same to have a wider range of movement than would be otherwise possible. The spring arms 2 and 3 normally diverge somewhat as they extend from the loop-shaped portion, as shown in Fig. 1, and the arm 2 is provided with an eye 5 adjacent the free end thereof, which may, if desired, be formed from a separate piece of material suitably 70 secured to the free end of the arm, but which, in the present instance, is formed by bending over a portion of the free end of the arm. A guard loop 6 is pivotally 75 secured in the eye 5 and is capable of swinging freely therein for engagement with and disengagement from the free end of the arm 3.

The guard loop 6 is provided with an angular lip portion 7 extending in angular direction from the plane of the main body portion of the loop and adapted to extend substantially parallel and contact with the outer surface of the arm 3 when in latching position, as shown in Fig. 3. The lip portion 7 terminates in an inturned projection 8, which is adapted to be received in an opening or recess 9 formed in the free end of the arm 3 when the guard loop is turned to latching position, thus providing means for holding the arms 2 and 3 against relative longitudinal movement and preventing accidental disengagement of the arm 3 from the guard loop. The end of the arm 3 is outturned slightly, as indicated at 10, to closely engage 100 the guard loop.

The form of the invention shown in Figs. 4 and 5 is in all respects similar to that above described, except that a different form of guard loop is employed and the free end of the arm 3 is correspondingly modified for engagement with the guard loop. The guard loop 12 is formed with its sides 13 inclined

slightly towards each other as they extend from the eye 5, whereby the outwardly-extending portion of the guard loop is of less width than the portion positioned within the eye 5, to better engage recessed notches 14 formed in opposite sides of the narrowed end portion 15 of the free end of the arm 3 and thus hold the arms against relative longitudinal movement when the parts are in latched position. As in the form previously described, the extreme end of the arm 3 is outturned slightly, as indicated at 11.

In the form disclosed in Figs. 6 and 7, the guard loop 16 is provided with an inturned projection 17 adapted to engage in an opening or recess 18 formed in the free end of the arm 3 to latch the arms 2 and 3 together and positively prevent accidental disengagement of the same.

The form shown in Figs. 8 and 9, as in the forms previously described, comprises resilient normally divergent arms 2 and 3, the arm 2 being provided adjacent its free end with an eye 5 for pivotally supporting a guard loop for holding the free ends of the arms in latched position. The guard loop 19 is pivotally supported in the eye 5 and is provided with an angular lip portion 20 extending in an angular direction from the plane of the main body portion of the loop and adapted to extend substantially parallel to and contact with the outer surface of a depressed recess 21 formed by bending inwardly the free end of the arm 3.

Since the angular lip portion 20 fits closely against the outer surface of the depressed portion 21, the arms 2 and 3 are securely latched together and firmly held against accidental disengagement.

It is to be understood that various changes may be made in the shape and ar-

rangement of the parts shown and described without departing from the scope of the invention as defined in the appended claims.

What I claim is:—

1. A hair-clasping device, comprising, an elongated strip of resilient material bent upon itself to form normally divergent arms, one of said arms being provided adjacent its free end with an eye, and a guard loop pivotally mounted in said eye and provided with an angular lip portion overlying and fitting closely against the outer surface of the free end of the other arm when turned into engagement therewith. 45

2. A hair-clasping device, comprising, an elongated strip of resilient material bent upon itself to form normally divergent arms, one of said arms being provided adjacent its free end with an eye, the other of said arms 60 being provided adjacent its free end with a depression, and a guard loop pivotally mounted in said eye and having a lip portion extending at an angle to the main body portion of said loop and engageable with 65 the depressed portion of said last-named arm when the parts are in latched position. 55

3. A hair-clasping device, comprising, an elongated strip of resilient material bent upon itself to form normally divergent arms, one of said arms being provided adjacent its free end with an eye, the other of said arms being provided adjacent its free end with a recess, and a guard loop pivotally mounted in said eye and having an inturned lip projecting inwardly from the guard loop and engageable with the said recess in the last-named arm when the parts are in latched position. 75

In testimony whereof I have affixed my 80 signature.

BLANCHE ELSIE BEADLE.
